ELECTRIC DISCHARGE TUBE

Application filed January 19, 1928, Serial No. 248,017, and in Germany January 20, 1927.

This invention relates to an electric rectifier having one or more anodes and an incandescent cathode, which emit a sufficient stream of electrons at a comparatively low temperature, which is substantially below the disintegration temperature and consequently the melting point.

The object of the invention is to provide rectifiers with cathodes of the character above referred to which will be capable of being used for higher voltages or currents, or both, than has hitherto been possible. By means of the rectifier constructed according to the invention, it is possible to rectify alternating currents of any desired frequency even when the maximum voltage of 250 volts is reached or exceeded, it being possible to control voltages which are even higher than a multiple of 2,500 volts. It is also possible to use the rectifier according to the present invention for controlling currents of many amperes which was not hitherto possible to control with rectifiers having a solid cathode enclosed in a glass vessel.

It has already been proposed to construct rectifiers with a cathode of pure tungsten and a filling of inert gases, the pressure of the gas being greater than 1 mm. column of mercury. However, it has not been possible to control by means of such rectifiers voltages and currents having the maximum value which can be obtained by the rectifier according to the present invention.

Corresponding to the low pressure also the gas filling will require a smaller amount of gas and consequently there will be a saving in the very expensive gas, such as argon, neon and helium. If use is made instead of such a rare gas, of nitrogen or metal vapours, the advantages concerning the saving in expenditure are, it is true, less important. However, the smaller gas content is also connected with a smaller heat conductivity and consequently the transfer of heat from the incandescent cathode to the vessel of the rectifier, which is preferably made of quartz, glass or the like, is reduced. In consequence thereof also, the surface of this vessel which radiates the heat can be made smaller without its reaching inadmissible high temperatures. This leads

first of all to a smaller glass vessel or the like and the cost of manufacture of the rectifier is also reduced, whilst the construction is simplified and the device requires less space for its accommodation.

By reducing the transfer of heat of conduction also the heating current which is required for maintaining the temperature of emission of the incandescent cathode is correspondingly smaller, since the same has now to make up for a smaller loss of heat caused by conduction.

If the heating current is thus reduced it follows that for the same output the leading in wires for the heating current required for the incandescent cathode can also be of small diameter; and vice versa if the said leads are not altered, it is possible to control substantially greater emissions of electrons and therefore larger currents which have to be rectified.

Further, the surprising result has been ascertained that in spite of the use of such a low pressure for the same output the temperature of incandescence can be further reduced, whereby the life of the cathode is substantially increased. One of the reasons therefor may consist in this that owing to the reduction of the gas content by the reduction in pressure and by reducing the size of the vessel also the number of gas ions which impinge upon a cathode of given surface and which, on the one hand have an additional disintegrating effect and, on the other hand, a neutralizing effect upon the electrons, is reduced.

This advantage is especially noticeable in the case of incandescent cathodes made of a primary material which is capable of greater disintegration at the same temperature as compared with pure tungsten, such as for instance, molybdenum and also in the case of such cathodes, which contain an additional substance such as thorium and uranium capable of facilitating the emission of electrons, such material being active on the outer surface of the cathode and capable of being split by the gas ions impinging thereon.

The molybdenum used as base metal allows the incorporation of more thorium ox-

ide than e. g. tungsten without losing ductility even if being cold. Furthermore, such molybdenum in the form of a wire can be wound in narrow coils even if it has a quite large diameter and therefore an emitting surface larger than a tungsten wire. Lastly, by the molybdenum acting as a catalyst on the thorium oxide the reactivation of the cathode during operation is assured because substantially reduced thorium-oxide, i. e. metallic thorium is now diffusing from the inner of the body of the cathode to its outer surface and there replacing any thorium which has disappeared by splitting or evaporation.

A further advantage of the invention lies in this that with a given voltage the electrodes can be arranged nearer to one another than in the case of a higher gas pressure as hitherto used; vice versa, with a given distance between the electrodes higher voltages can be controlled. This also explains why it is possible to use a rectifier according to the present invention in connection with high voltages which were hitherto impossible to control by means of glass vessel rectifiers.

Whatever may be the nature of the inert gas with which the vessel is filled the said gas always contains impurities because it is only in the laboratory and not in large works that use is made of methods for purifying the gas. It therefore follows that when the pressure and consequently the amount of filled gas is reduced also the amount of impurities introduced into the vessel with the gas is also reduced. Further, as has already been pointed out above the actual contents of the vessel can be reduced also with a given voltage or current or output and consequently the amount of impurities that can be introduced is further reduced. However, these impurities, according to the present scientific knowledge, constituted one of the reasons which reduced the life of the incandescent cathode since, during the operation these impurities are deposited on the incandescent cathode and adhere thereto, thereby covering otherwise active surface elements of the cathode and preventing them from taking part in the further emission of electrons.

The impurities above referred to constituted, also according to the knowledge of the art which may or may not be correct, the reason why certain minimum distances between electrodes of the same polarity, that is to say anodes, had to be maintained in order to avoid direct leakage between these electrodes, without reaching the cathode. By the amount of impurities being reduced, according to the invention also the possibility of a direct leakage is reduced and this explains why in a rectifier according to the invention the distance between the electrodes and consequently also the dimensions of the

vessel and more particularly its gas contents can be further reduced.

The accompanying drawing is a diagrammatical section through a rectifier according to the invention. The invention is of course not limited to the sketch shown.

1 is a glass bulb or vessel with a so-called plug 2 provided with a foot contact 3 and also screw contact 4 and further two loop-like terminals 5 and 6, these contacts or terminals being insulated from each other by the glass of the plug 2.

In the vessel 1 is arranged a cathode 7 of a homogeneous molybdenum wire containing thorium, thorium oxide or both in an amount from .25 up to 10%. This cathode is connected at its ends by leading-in wires 8 and 9 respectively with the contacts 4 and 3 respectively. Anodes 10 and 11 respectively are arranged on opposite sides to the helically wound cathode 7 and connected with the leading-in wires 12 and 13 respectively with the terminals 5 and 6 respectively. The vessel is first evacuated and the electrodes are, if needed, freed from occluded gases, whereupon a filling of inert or rare gases is introduced at a pressure of about 3 to 30 millimeters.

The anodes may be made of any material which, when the surface by which the current enters is properly dimensioned is not disintegrated by the heating up which is unavoidable. More particularly the anode may be made of tantalum, tungsten, molybdenum, nickel, graphite and even iron.

With these as primary material, thorium, thorium oxide or other metals and metalloids which are different from the primary material, are employed as the additional substance and also to cathodes in which a mixture of the mentioned primary substances is employed with an additional substance or a mixture of additional substances. With tungsten as primary substance for the cathode, 0.25 to 10% of thorium is a suitable addition.

A rectifier according to the present invention is manufactured in the same way as other electric vacuum vessels filled with gas or metal vapours at a lower pressure than 30 mm. mercury column. First of all the vessel is deprived as much as possible of occluded gases and adhering water vapour by heating, and is thereupon actuated as much as possible, whilst the gases are removed from the electrodes. The inert gas or metal vapour or a mixture thereof is thereupon introduced into the vessel until it reaches the pressure lower than 30 mm. mercury column required according to the present invention, whereupon the vessel is removed from the pump and is sealed up.

The discharge vessel or rectifier may be constructed in any known or suitable manner, more particularly the vessel, if intended for

a rectifier, may be made tubular, the cathode being arranged at one end and the anode at the other end, or, the cathode may be arranged in the centre and one anode at each end. When the construction embodies two or more anodes a central part may be provided for the reception of the cathode onto which are formed a number of preferably bent arms corresponding to the number of anodes, the latter being built-in in the proximity of the end of the corresponding arm.

What I claim is:—

1. An electric rectifier comprising an electric discharge vessel having an anode, a cathode of molybdenum and an addition of from 0.25% to 10% thorium oxide, the molybdenum acting as a catalyst on the thorium oxide to reduce the same to metallic state, and a filling of inert gas in said vessel at a pressure from about 3 mm. up to about 30 mm. mercury column.

2. An electric rectifier comprising an electric discharge vessel having an anode, a cathode of molybdenum and an addition of from 0.25% to 10% thorium, in metallic state, and a filling of inert gas in said vessel at a pressure from about 3 mm. up to about 30 mm. mercury column.

In testimony whereof I have signed my name to this specification.
